United States Patent Office

Des. 194,038
Patented Nov. 13, 1962

194,038

COMBINED TABLE AND SEATING UNIT

Enos C. Preston, Rte. 2, Box 359, Troutdale, Oreg.

Filed Oct. 9, 1961, Ser. No. 67,011

Term of patent 14 years

(Cl. D33—14)

FIG. 1

FIG. 2

I claim:

The ornamental design of a combined table and seating unit, as shown.
